UNITED STATES PATENT OFFICE.

SIDNEY E. ESKEW AND LEWIS HARRIS, OF BENTON, ILLINOIS.

SMOOTHING SHEET.

Application filed January 8, 1923. Serial No. 611,436.

To all whom it may concern:

Be it known that we, SIDNEY E. ESKEW and LEWIS HARRIS, citizens of the United States, residing at Benton, in the county of 5 Franklin and State of Illinois, have invented new and useful Improvements in Smoothing Sheets, of which the following is a specification.

This invention relates to abrading devices 10 and has for its object the provision of a smoothing sheet of novel formation designed to exert a smoothing action when rubbed upon wood or the like and designed to replace the ordinary sand paper, emery 15 cloth or steel wool which are commonly used for this same purpose.

An important and more specific object is 20 the provision of an abrasive sheet which is itself provided with a plurality of cutting edges which will operate to smooth any material worked on instead of scratching it as is the action when the ordinary materials, such as sand paper and the like are used, it being well known that sand 25 paper, emery cloth and the like are objectionable inasmuch as grains of sand or emery which become loosened from the sheet embed themselves in the material worked on and subsequently work out and 30 show up when the work is varnished or otherwise treated to effect finishing.

An additional object is the provision of 35 an abrasive sheet which will be simple and inexpensive in manufacture, highly efficient in use, durable in service and a general improvement in the art.

With the above and other objects and advantages in view the invention consists in the details of construction to be hereinafter 40 more fully described and claimed and illustrated in the accompanying drawings, in which:

Figure 1 is a plan view of one form of the 45 abrasive sheet,

Figure 2 is a greatly enlarged section therethrough,

Figure 3 is a plan view of another form and

Figure 4 is a greatly enlarged section 50 therethrough.

Referring more particularly to the drawings and especially to Figures 1 and 2, we have shown the abrasive sheet as being formed from any suitable size sheet 10 of 55 steel of any preferred gage. This sheet

is provided with a file like surface at either or both sides. In actual practice this rough surface may be formed by scratching or scoring the sheet, preferably diagonally as shown at 11, after which the sheet is 60 tempered to give it the requisite hardness. These scratches or scores provide a plurality of continuous cutting edges indicated in greater detail at 12 in Figure 2, this view being a greatly magnified section through a 65 portion of the sheet.

In Figures 3 and 4 the sheet is shown as 70 being of a reticulated nature, that is it is cut or stamped with a plurality of openings or holes 13 of any desired size and shape arranged preferably in diagonal rows and having their edges formed with burrs more clearly indicated at 14 in Figure 4 which is a magnified section through this second type of sheet.

In the use of either form of the invention the material to be smoothed is rubbed with the abrasive sheet in the same manner as sand paper or emery cloth is used, except that it is intended that the movement be 80 fully reciprocatory and not a circular or scoring movement, though of course this might be resorted to if found advisable. The great advantage in the use of either type of sheet is that it acts in the nature of a plane 85 and removes minute shavings instead of scratching the surface as is the result when the ordinary sand paper sheet is used. As the abrasive sheets are tempered, they will naturally be brittle so that they may be 90 easily broken into any desired size depending upon the nature of the work to be done.

While we have shown and described the preferred embodiment of the invention it is 95 of course to be understood that we reserve the right to make such changes in the form, construction and arrangement of parts as will not depart from the spirit of the invention or the scope of the subjoined claim.

We claim:

An abrasive sheet of slightly flexible metal but of a sufficiently brittle nature to permit breaking into pieces of desired size, the sheet being formed on one face with a roughened surface.

In testimony whereof we affix our signatures.

SIDNEY E. ESKEW.
LEWIS HARRIS.
